UNITED STATES PATENT OFFICE.

STUART J. CLARK, OF AUBURN, ILLINOIS.

DESIGN FOR A BADGE.

45,855.

Specification for Design.

Patented June 2, 1914.

Application filed January 12, 1914. Serial No. 811,770. Term of patent 14 years.

To all whom it may concern:

Be it known that I, STUART J. CLARK, a citizen of the United States, residing at Auburn, in the county of Sangamon and State of Illinois, have invented a new, original, and ornamental Design for Badges, of which the following is a specification, reference being had to the accompanying drawing, forming part thereof.

Figure 1 is a plan view of the face of a

badge showing my design, and Fig. 2 is a plan view of the back of a badge showing my design.

I claim:—

The ornamental design for a badge as shown.

STUART J. CLARK.
